(57) **CLAIM**

The ornamental design for an outdoor versatile collapsible toy set, as shown and described.

DESCRIPTION

FIG. 1 is an isometric view of all components of the assembly and the order of combining thereof, the components of the assembly comprising a collapsible bucket, a collapsible water sprinkler, a rack-n-shovel set, and a Frisbee serving as a snap-on top;

FIG. 2 is a side view of the complete assembly;

FIG. 3 is an isometric view of the complete assembly;

FIG. 4 is an isometric view of the rake-n-shovel assembly in its folded position;

FIG. 5 is an isometric view of the rake-n-shovel assembly in its slightly unfolded position;

FIG. 6 is a side view of the bucket assembly in its extended position;

FIG. 7 is a magnified and detailed view of the locking mechanism for the bucket assembly to ensure a secure locking of said assembly in collapsed and extended positions;

FIG. 8 is a side view of the bucket assembly in its collapsed position;

FIG. 9a is a top view of the collapsible water sprinkler;

FIG. 9b is a side view of the water sprinkler in its extended position;

FIG. 10 is an isometric view of the water sprinkler in its extended position;

FIG. 11 is a side view of the water sprinkler in its collapsed position; and,

FIG. 12 is an isometric view of the water sprinkler in its collapsed position.

The design of the bucket and the water sprinkler assembly has a flat bottom that is unornamented and a view thereof is omitted from the specification. The subject matter shown in broken line represents unclaimed environmental structure which is shown for illustrative purposes and forms no part of the claimed design.
